UNITED STATES PATENT OFFICE.

WALTER D. WOOD, OF ALLENTOWN, PENNSYLVANIA, ASSIGNOR TO FUEL SAVING COMPANY, OF ALLENTOWN, PENNSYLVANIA, A CORPORATION OF PENNSYLVANIA.

LOCOMOTIVE-FURNACE.

1,292,205.

Specification of Letters Patent. Patented Jan. 21, 1919.

Application filed July 13, 1917. Serial No. 180,297.

To all whom it may concern:

Be it known that I, WALTER D. Wood, a citizen of the United States, and resident of Allentown, in the county of Lehigh and State of Pennsylvania, have invented certain new and useful Improvements in Locomotive-Furnaces, of which the following is a specification, reference being had therein to the accompanying drawing.

10 My present invention refers to certain new and useful improvements in the firing chambers or boxes of locomotives and other furnaces, having for its primary object the regulation of the supply of air, so that the combustion of the fuel may take place in the most approved and efficient manner, the invention being particularly applicable to those furnaces wherein fine or powdered fuel, such as coal dust, is burned. The invention consists essentially in means for supplying outside atmospheric air at certain necessary points in order to subserve special combustive and other results, and in valve or damper mechanism for regulating 25 and controlling the supply, and also in various details and peculiarities in the construction, arrangement, and combination of the several mechanical parts which coöperate and carry out the object in view, substantially as will be hereinafter described and then more particularly pointed out in the claims.

In the accompanying drawing illustrating my invention:

35 Figure 1 is a vertical section of my improved firing chamber for powdered fuel;

Fig. 2 is a transverse section of the same on the line 2, 2 of Fig. 1;

40 Fig. 3 is an outside end view showing more particularly the operating mechanism for the dampers;

Fig. 4 is a side elevation of my improved firing chamber and illustrates more particularly the damper mechanism;

45 Fig. 5 is a detail view of the lever for operating the damper mechanism with its clicking spring catch;

Similar characters of reference designate corresponding parts throughout the different figures of the drawing.

1 denotes the firing box of any ordinary locomotive or other engine furnace or the like. Said firing chamber is not usually built in the common manner, but the space which is generally occupied by the grates, 55 ash pan, etc., is in this newly devised form replaced by an auxiliary chamber 2, depressed quite a little below the usual level of the bottom of the fire box, which depressed chamber is sheathed with fire brick. 60 Above the depressed auxiliary chamber at a suitable height is an inclined arch consisting ordinarily of a series of inclined water tubes 6 that support the fire brick 5, there being at the rear end of the arch, which is 65 the upper end, an opening 7, through which the flame may pass from below the arch to the space above the same. The fuel consisting of finely pulverized coal, anthracite culm, or other finely granulated material, is 70 fed into the chamber 2 under a strong air or steam blast, entry being made at the door 4, at which point the fuel-laden vehicle enters, and also, if desired, additional quantities of properly measured and regulated air 75 coming directly from the atmosphere or otherwise. Further, it will be seen that in the bottom of the chamber 2 there is an opening 9 for the removal of slag or any other foreign matter formed in the process 80 of combustion, which it is necessary or desirable to take away so that the operation of the furnace will not be obstructed, and with said opening 9 a slag pan or other receptacle (not shown) is generally operated. 85

In order to facilitate the combustion of the fine fuel within the firing chamber in accordance with the principles of the present invention, I introduce an additional quantity or quantities of atmospheric air at the front 90 end of the fire box, and in order to do this, I provide a suitable number of ducts 8 formed by fire brick or in other ways in the front wall 3 of the fire box, said ducts having openings 8^a at the lower end through 95 which the air is directly introduced from the atmosphere, and having openings 8^b at the upper end through which air is delivered into the interior of the firing chamber 1 at a point immediately below the arch; hence, 100

it will be understood that atmospheric air is brought in directly from the outside and follows up beneath the rows of bricks along the ducts 8 (see Fig. 2), and is then allowed 5 to flow into the firing chamber immediately beneath the lower portion of the arch where it will instantly follow up underneath the surface of the arch and mingle with the entering coal dust or comminuted fuel which 10 is being fed into the firing chamber through the main door 4, thus helping to consume said coal dust.

There are various leading objects in admitting this air in the manner shown. First, 15 it has been found in actual practice that the arch has a tendency to burn through at a point somewhere near that marked A in Fig. 1, which is a point a certain distance from the front end toward the rear opening 20 7, say one-third of the distance, it being noted that the burning through of the arch takes place more quickly at this than at any other place, for it would seem that here there 25 is the most intense heat, and the impinging or firing action on the brick work has the most destructive effect. By admitting air in the manner indicated, I provide continually a film of comparatively cool air; that 30 is to say, air which is cool in comparison with the temperature of the flame, and this cool air spreading and sweeping along underneath the arch will tend to reduce the temperature of this particularly sensitive part sufficiently to prevent any destructive 35 action of the fire on the fire brick.

Secondly, by passing the air up alongside of the front inside brick wall 3, I am enabled to keep this brick work comparatively cool and prevent destructive action 40 of the flame on its opposite flame-exposed surface, as at B (see Fig. 1) for it is found that if the brick work 3 is kept comparatively cool on one side any destructive action of fire or flame on the opposite side 45 can only proceed a certain distance when its progress will be arrested by striking the cool area of the brick.

Another very vital feature in this construction and arrangement of parts which 50 I am now describing, is the fact that at times a certain amount of partly consumed coal will be carried over the rear of the arch and through the rear opening 7 along the path marked by arrows at C, such action 55 being a sort of short-circuiting, so that a portion of the fuel passes over the top of the arch through the opening 7 in a semi-consumed state, or in other words without having enough oxygen to complete the combustion. 60 This causes a considerable deposit of the so-called honeycomb, which is nothing more or less than unburned coal, on the flue sheet. Ordinarily the gases follow along the path marked by arrows at E. By ad-

mitting air copiously at the front through 65 the plurality of ducts already provided and causing this air to travel along underneath the arch and close thereto, I am enabled to add more air at the point D immediately below the opening 7, which air will mingle 70 with the partly consumed coal and complete the combustion. This is very necessary, as it should be apparent that once the coal enters the zone which I have indicated at D, it is impossible to add more air for combustion 75 from below, and unless some method similar to that which I have devised and am now describing is availed of to admit additional air in the zone D to combine with this unburned coal and change CO to CO₂ it must 80 necessarily follow that we will be hampered by smoke and honeycomb troubles.

Referring next to Figs. 1 and 2 it will be noted that I provide openings for air at other places besides the front ducts 8. These 85 additional openings are the rear opening or openings 10 in the rear wall of the chamber 2 near the bottom thereof and contiguous to the main fuel door 4. There is also a lower row of openings 11 in both of the 90 longitudinal side walls of the chamber 2, and another upper row of openings 12 at a distance above each row of openings 11. All the openings 12 on each side of the furnace are controlled by a single damper on 95 each side of the firing chamber as are also all the openings 11 on each side of the firing chamber, and all of said dampers on both sides are preferably linked together by suitable operating levers which may be jointly 100 actuated.

Thus it will be seen by referring to Figs. 3 and 4 that there is an upper damper 13 on each side of the furnace, which functions with the upper row of openings 12 and 105 a lower damper 14 which functions with the lower row of openings 11. The dampers 13 are carried by horizontal shafts 15 supported in suitable bearings 15^a, while the lower dampers 14 are carried by horizontal rods 16 supported in bearings 16^a. The shafts 15 and 16 on the opposite sides of the furnace are connected together for joint 110 operation by suitable means, as for example, the link 25, which is pivoted at one end to a crank arm 24 that is rigidly secured to one of the shafts 15 while the other end of said link 25 is connected to a crank arm 30 rigidly carried by the other shaft 15 on the opposite side of the furnace. Also a link 115 29 is connected to a crank arm 31 carried by one of the horizontal shafts 16 at one side of the furnace, and at its opposite end said link 29 is connected to a crank 28 affixed to the other rod 16; further at one side of the furnace a link 27 runs from the crank arm 28 to a crank arm 26 secured to the shaft 15 on that side of the furnace. I also

provide the same shaft 15 with another crank arm 23, to which is pivoted a vertical link 22 whose upper end is pivotally attached to an arm 21 projecting from an operating handle 17 which is movably mounted at 32 on some suitable part of the exterior of the furnace, and said operating handle 17 is provided with a spring detent 18 which acts in connection with the notches 15 which are in the notched sector 19. Thus the attendant can by a suitable manipulation of the handle 17 operate the dampers 13 and 14 at the same time on both sides of the furnace and control the supply of air entering through the openings 11 and 12.

It will be observed that when these dampers 13 and 14 are closed, two complete damper boxes are formed, as will be seen by reference to the position of these parts in Fig. 2, so that practically no air when they are so closed will be admitted to the fire box. When they are open, as they are indicated in Fig. 2, an ample supply of auxiliary air may be introduced. The openings 10, of which there may be any suitable number, in front of the firebox are shown as unprovided with dampers, as are also the ducts 8 and the entrance 8^a at the lower ends of the ducts, but it will be readily understood that if desired these openings 8 and 10 may also be furnished with suitable valves or dampers for controlling the supply of air passing through them. When the fireman or other attendant desires to change the air supply, all that he needs to do is to vibrate the lever 17 in one direction or the other, pushing it either ahead or back, and the steel spring 18 with which it is provided will function as a detent and will slide over the notches in quadrant 19 and stay in any fixed position as desired. A useful feature of this arrangement is that the fireman can tell by the number of clicks as the spring snaps into the notches, just how many notches he is moving the damper, and consequently how much he is opening or closing the air openings without being required to specially inspect the same or investigate by looking at the dampers, said audible means giving him all the information required.

It will, therefore, be seen that I attain by the air supply arrangements which I have described many useful and valuable advantages in promoting combustion and making the same uniform in different parts of the furnace, and also preventing the undue heating and burning out of some of the parts, and such a regulation of the air supply is proven to be of great importance in the burning of fine fuel in locomotives and other furnaces.

Many changes in the detailed construction of various parts may be made without ex-

ceeding the scope of the invention, and I reserve the liberty to make these changes. I am not restricted to any form or shape of furnace or its interior arch, and neither am I confined to any particular number of the ducts 8 or any special shape or location of the same, or of openings 10, 11 and 12, inasmuch as the same may be made in any desired manner and may be either made by the removal of one or more bricks or may be cut through the bricks or may be fitted with bushings or pipes or otherwise in order to secure the best results in practice.

Having thus described my invention, what I claim as new and desire to secure by Letters Patent, is:—

1. In a locomotive furnace for powdered fuel, the combination with a fire box having a depressed auxiliary chamber receiving the powdered fuel and having also an arch extending from front to rear, of a plurality of ducts lying along the front wall of the furnace and conveying outside air to a point immediately below the arch where it is permitted to flow beneath said arch to protect the latter from burning out and to promote the process of combustion, said ducts being formed on three sides by brick work and the fourth side being formed by the front sheet of the combustion chamber and also of the throat sheet of the locomotive boiler.

2. In a locomotive furnace for powdered fuel, the combination with a firing chamber receiving the powdered fuel at one point and provided with an inclined interior arch extending from front to rear, of a series of ducts arranged in connection with the front wall of the furnaces so that the rear sides of these ducts are open for their entire length to the front wall of the combustion chamber and the throat sheet of the locomotive fire box, said ducts being open to the atmosphere at one point and open to the interior of the furnace at another so that outside air may be conveyed into the furnace immediately below the arch where it is permitted to spread into a film of cool air to prevent destructive action of the flame on the fire brick of the arch.

3. In a locomotive furnace for powdered fuel, the combination with a firing chamber having a depressed auxiliary chamber which receives the powdered fuel at one point, of a series of upwardly extending ducts arranged in connection with the front wall of the furnace, said ducts being open to the atmosphere at one point and to the interior of the furnace at another and conveying cool outside air to protect the front wall from destructive action of the flame against the inside thereof, and said ducts beginning at a point directly beneath the inclined arch and running downwardly to a point in the front of the combustion chamber where air

is admitted, so that the entering air will come in contact on three sides of the duct with hot fire brick while on the fourth side it will be kept comparatively cool by being in contact with the front sheet of the combustion chamber and the throat sheet of the fire box during the entire length of its travel till it is delivered into the fire box proper.

4. In a furnace or chamber employing fine fuel, the combination of a fire box having a depressed auxiliary chamber receiving the powdered fuel at one point and having also an arch extending from front to rear and provided with an opening through the same, of a series of upwardly extending ducts arranged in connection with the front wall of the furnace and receiving outside atmospheric air and conveying the same to the interior of the furnace at a point immediately below the arch to provide a film of comparatively cool air so that the front wall and the arch may be protected against the destructive action of the flame and the incomplete combustion of part of the fuel through short-circuiting through the opening in the arch may be prevented, said atmospheric air being kept cool by being passed over the comparatively cool surface of the front sheet of the combustion chamber and the throat sheet of the locomotive, the duct being so formed as to leave these two cool surfaces exposed to the entering air.

5. In a locomotive furnace for powdered fuel, the combination with a firing chamber having a depressed auxiliary chamber which receives the powdered fuel at one point, of a series of upwardly extending ducts arranged in connection with the front wall of the furnace for conveying outside air to the interior of said furnace, said ducts being formed by leaving hollow spaces in the front wall of the furnace, the front sheet of the combustion chamber and the throat sheet of the furnace being utilized to form one of the four sides of this duct, and lateral valve devices for admitting additional outside air to the interior of the furnace, together with mechanism for operating said valve devices.

6. In a locomotive furnace for powdered fuel, the combination with a firing chamber receiving the powdered fuel at one point, of a series of air-admitting ducts arranged in connection with the front wall of the furnace, one or more air-admission openings located contiguous to the main door in the rear wall, an upper series of openings in each longitudinal side wall of the furnace, and a second series of openings below the latter series and nearer to the bottom of the furnace, together with suitable valve mechanism for the longitudinal series of openings, all of the dampers or valve mechanism

being jointly connected so that they can all be entirely open, entirely closed or fixed at any point between these two specified by moving a single controlling lever placed in the cab of the locomotive adjacent to the seat occupied by the fireman, thus enabling instantaneous adjustable control of the amount of atmospheric air entering the fire box at all times.

7. In a locomotive furnace for powdered fuel, the combination with a firing chamber, of a series of air ducts arranged in connection with the front wall of the furnace, air-admission openings in the rear wall of the furnace, a series of lateral openings in each longitudinal side of the furnace, valve devices for the latter openings, said devices consisting of longitudinal shutters, and means for operating them including lever devices and a single actuating handle, all of the dampers or valve mechanism being jointly connected so that they can all be entirely open, entirely closed or fixed at any point between these two specified by moving a single controlling lever placed in the cab of the locomotive adjacent to the seat occupied by the fireman, thus enabling instantaneous adjustable control of the amount of atmospheric air entering the fire box at all times.

8. In a locomotive furnace for powdered fuel, the combination with a firing chamber which receives the powdered fuel at one point, of a series of air ducts in the front wall, said air ducts having inlets and outlets, means for admitting air at the longitudinal sides of the furnace, and damper means for controlling said air-admission means, said damper means consisting essentially of hinged shutters having operating mechanism composed of interacting levers under the control of a single lever handle provided with a clicking catch, all of the dampers or valve mechanism being jointly connected so that they can all be entirely open, entirely closed or fixed at any point between these two specified by moving a single controlling lever placed in the cab of the locomotive adjacent to the seat occupied by the fireman, thus enabling instantaneous adjustable control of the amount of atmospheric air entering the fire box at all times.

9. In a locomotive furnace for powdered fuel and the like, the combination of a firing chamber having a main inlet for the fuel, air-admission ducts located in the wall opposite to the main inlet and admitting air in such a manner as to protect said wall and also to convey air to the interior of the furnace so as to prevent incomplete combustion of the fuel before it is carried over the arch, means for admitting air at the longitudinal sides of the furnace consist-

ing of rows of openings, and longitudinal damper devices at the opposite sides of the furnace, two on each side, said damper devices being provided with longitudinal shafts, lever connections between said shafts for jointly rotating the damper shafts and controlling the dampers, and a single con-

nected lever for jointly moving the dampers on both sides, said lever being provided with a detent.

10

In testimony whereof I hereunto affix my signature.

WALTER D. WOOD.
